UNITED STATES PATENT OFFICE.

WILLIAM W. ROBERTSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

CHECK FOR AXMINSTER-LOOM NEEDLE MOTION.

Application filed November 30, 1925. Serial No. 72,091.

This invention relates to improvements in needle motions for Axminster looms and it is the general object of the invention to prevent vibration of the eye end of the needle of such looms when running at a relatively high rate of speed.

Axminster looms usually employ a needle motion at one side of the loom and a selvage shuttle motion at the other side, the needle being projected through the shed and having a recess on the under side thereof which should register with the reduced end or nose of the selvage shuttle. When the needle comes to rest the shuttle moves from one side thereof to the other to interloop the selvage warp with the filling of the needle and after the shuttle has passed through the filling the needle is withdrawn. As heretofore operated the needles have been able to register properly with the selvage shuttle but attempts to operate looms of this type at a higher rate of speed have been found to cause vibration of the eye end of the needle to such an objectionable degree that the shuttle nose does not always pass through the looped filling. This is because of the fact that the needle moves transversely away from the path of movement of the shuttle. It is an important feature of my invention to provide devices adjacent the shuttle motion to engage and restrain undue vibration of the needle to the end that the shuttle may always pass through the loop of filling.

It is a further and more particular object of my invention to provide the shuttle actuator of the selvage shuttle motion with a slightly flexible shield or guard which is brought into position to resist movement of the needle away from the path of the shuttle, the shield or guard being moved out of position when not needed, thus rendering unnecessary any change in the type of shuttle actuator at present in use.

It is a further object of my invention to provide a checking device for the eye end of the needle so constructed that a portion thereof is fixed and immovable while another portion thereof is slightly yieldable and placed so as to form with the first portion a socket or pocket for receiving the eye end of the needle.

With these and other objects in view which will appear as the description proceeds, my invention resides in the combination and ar-

angement of parts hereinafter described and set forth in the claims.

In the accompanying drawings wherein I have shown a convenient embodiment of my invention,

Fig. 1 is a top plan view of a selvage shuttle motion and adjacent parts showing the needle at the extreme end of its weft laying stroke and with the shuttle partly moved through the loop of filling laid by the needle,

Fig. 2 is a vertical section on line 2—2 of Fig. 1, and

Fig. 3 is a detail vertical section on line 3—3 of Fig. 2.

Referring to the drawings it will be seen that I have provided a bracket 10 secured to and extending upwardly from a loom frame 11 and having an offset shelf 12. Extending upwardly from said shelf and freely rotatable therein is a shaft 13 to the upper end of which is secured a hub 14 by means of set screw 15. The upper face of said hub is provided with a slot 16 in which is located the foot 17 of a shuttle actuator 18, said foot being held to the hub by means of bolt 19. The inner end of said actuator 18 is provided with a pair of shuttle actuating depending pins 20 and 21, respectively, which have operative contact with the opposite ends of the selvage thread shuttle S.

The shelf 12 has bolted thereto a stand 22 to which is secured a shuttle race 23 arcuate in form and provided with flanges 24 and 25 as shown in Figs. 1 and 2. A thread guide 26 is secured to the flange 24 and is provided with an opening 27 through which the needle N may extend as shown in Fig. 2.

Shaft 13 has secured thereto an operating arm 28 pivotally connected to a rod 29 which is reciprocated in timed relation with the needle motion so as to move the shuttle actuator 18 and the shuttle S from the right hand end of the race 23 to the left hand end as the needle N is in the position shown in Fig. 1.

This movement interlaces selvage thread T delivered by the shuttle S with the weft W laid by the needle, the weft passing through the eye I of the needle as shown in Fig. 2. The lower strand of the weft W extends under the needle so that the nose 30 of the shuttle which passes through a recess 31 formed in the under side of the needle will pass over said lower strand. In this way the selvage thread and the weft are

interlooped to hold the weft as the needle is withdrawn to the right from the position shown in Fig. 2. The matter thus far described is of common construction and forms 5 no part of my present invention.

As previously stated when wide Axminster looms are operated at a higher rate of speed than has prevailed heretofore it is found that the eye end of the needle vibrates 10 to such an extent that the nose 30 of the shuttle cannot always pass over the lower strand of the weft because of the fact that the needle is above its proper position. In order to prevent this objectionable improp- 15 er placing of the needle I have provided a holder 40 secured to the stand 22 as shown in Fig. 2 and having an upper substantially horizontal portion 41 to which is bolted or otherwise secured a block 42 preferably of 20 fibre in the upper face of which is formed a groove 43. Said groove has the lower face thereof inclined to receive the lower face of the needle and the side walls of the groove 43 serve to prevent undue sidewise movement 25 of the needle in a plane parallel to the movement of the shuttle. It is found that the block 42 does not prevent all of the vibration of the needle and I have found it desirable to employ a shield or guard 44 secured to 30 the shuttle actuator 18 as shown in Figs. 1 and 2. Said guard has a broadened needle engaging end 45 with the under face slightly inclined as shown in Fig. 2 and positioned when the shuttle S is at the extreme right 35 hand end of the shuttle race to lie over the groove 43 and form with the latter a socket or pocket which the advancing end of the needle enters as the latter nears the end of its weft laying stroke. Said shield or guard 40 44 is preferably formed of sheet steel so as to be slightly resilient to absorb the shock of the advancing needle.

In operation the block 42 remains at rest 45 and the guard 44 moves with the shuttle actuator, moving over the block at the time the needle enters the notch of the block to prevent upward movement thereof and moving out of position after the needle has been brought to rest. It will be seen by referring 50 to Fig. 1 that the broadened end 45 is sufficiently wide to extend over the needle during the time that the nose of the shuttle is passing under the needle, thus insuring proper positioning of the latter at the beginning 55 of the stroke of the shuttle. The block 42 may be renewed as occasion requires and this is also true of the shield 44. While I have shown the shield or guard as being movable with the shuttle actuator yet 60 I do not wish to be held to this construction.

From the foregoing it will be seen that I have provided a simple means for preventing undesirable vibratory motion of the weft needle transverse to the fixed path in which 65 the selvage shuttle moves, thus causing the

eye end of the needle and the filling carried thereby to be properly positioned with respect to the selvage shuttle. It will further be seen that the shield or guard is in the form of a flexible member conveniently mounted on and movable with the shuttle actuator so as to be moved into operative position when desired without conflicting with the movement of the shuttle actuator. It will further be seen that the socket or 70 pocket for receiving the end of the needle is formed with two parts one of which is relatively fixed and the other of which is yieldable to absorb the shock of the advancing needle. 75

Having thus described my invention it will be apparent that changes and modifications may be made therein by those skilled in the art without departing from the spirit and scope of the invention, and I do not 80 wish to be limited to the details herein disclosed but what I claim is:

1. In an Axminster loom, a weft needle having a weft inserting movement, a shuttle for the selvage thread, means to move said shuttle from one side to the other side of the path of the needle when the latter is at the end of its weft inserting movement, and a guard carried by said means and positioned to engage and prevent vibration of the needle as the latter nears the end of its stroke. 90

2. In an Axminster loom, a weft needle having a weft laying stroke, a shuttle, means to move the shuttle from one side to the other side of the path of the needle when the latter is at the end of its weft laying stroke, a guard mounted on and moving with the means and positioned when the shuttle is at the beginning of its operative movement with respect to the needle to engage the latter and prevent lateral vibration thereof. 100

3. In an Axminster loom, a weft needle having a weft inserting stroke, a shuttle for the selvage thread, means to move the selvage shuttle from one side to the other side of the path of the needle when the latter is at the end of its weft inserting stroke, a yielding guard mounted on and moving with the means and positioned when the shuttle is at the beginning of its stroke to engage the needle and prevent lateral vibration thereof, to the end that said needle may be correctly positioned with respect to the shuttle as the latter is moved by said means. 110

4. In a needle motion for Axminster looms, a weft needle having a weft inserting stroke, a shuttle, means to move the shuttle from one side to the other side of the path of the needle when the latter has reached the end of its weft laying stroke, a fixed member having an opening therein to receive a portion of the needle, and a second member secured to and movable with the 120

means into proximity with respect to the first named member to form therewith a pocket to receive the needle and prevent lateral vibration thereof, to the end that said 5 needle may be properly positioned with respect to the shuttle as the latter is moved by the means.

5. In an Axminster loom, a weft needle having a weft inserting movement, a shuttle movable from one side to the other side 10 of the path of the needle when the latter has reached the end of its weft inserting stroke, and means defining a pocket to receive the advancing end of the needle and prevent lateral vibration thereof, said means including a pair of members one of which is relatively immovable and the other of 15 which is slightly resilient, said members engaging opposite sides of the needle.

6. In an Axminster loom, a weft needle 20 having a weft inserting stroke, a shuttle for the selvage thread, a shuttle actuator to move said shuttle from one side of the needle to the other side thereof, and a guard secured to and moving with the actuating 25 means and extending over the needle when the latter completes its weft inserting stroke, said guard being sufficiently broad to overlie the needle at the beginning of the stroke of the shuttle to prevent displacement of the 30 needle transversely of the path of the shuttle until after the advancing end of the shuttle has passed from one side to the other side of the needle.

In testimony whereof I have hereunto affixed my signature.

WILLIAM W. ROBERTSON.
